UNITED STATES PATENT OFFICE.

TILDA B. LEMAN, OF RAPID CITY, SOUTH DAKOTA.

NURSERY-CHAIR.

1,178,527.

Specification of Letters Patent. Patented Apr. 11, 1916.

Application filed July 3, 1914. Serial No. 848,823.

To all whom it may concern:

Be it known that I, TILDA B. LEMAN, of Rapid City, in the county of Pennington and State of South Dakota, have invented 5 certain new and useful Improvements in Nursery-Chairs; and I do hereby declare the following to be a full, clear, and exact description of the invention, such as will enable others skilled in the art to which it 10 appertains to make and use the same.

This invention relates to improvements in nursery chairs,—one object of the invention being to so construct the device that the sides and ends shall be of such height 15 as to prevent the child from falling out even when in a standing position.

A further object is to construct the device in such manner as to confine a child comfortably therein and so that it will not 20 be liable to be accidentally overturned, and yet be easily movable from place to place.

A further object is to provide a double seat, one portion of which is padded and movable with respect to the other portion, 25 the latter having a central opening, and to provide ready access to the space below said seat from the rear of the chair.

With these and other objects in view the invention consists in certain novel features 30 of construction and combinations of parts as hereinafter set forth and pointed out in the claims.

In the accompanying drawings, Figure 1 is a perspective view of a nursery chair embodying my improvements, and Fig. 2 is a 35 sectional view.

The body 1 of the chair has a general rectangular shape comprising front and back walls 2—3, sides 4—4 and a bottom 5,—all 40 of which may be conveniently made of wood.

The back 3 is made of considerable height (approximately equal to the height of a child who is beginning to stand) and is preferably made flaring toward its upper end.

45 The rear portions 6 of the sides 2 are made of a height approximating that of the back 3, while the forward portions of said sides are appreciably shorter in height and support a table 7, the latter being made partly 50 circular in form and extending over the upper end of the front 2. The table 7 may project outwardly beyond the front 2 and sides 4 and be provided at its outer curved edge with an upwardly projecting flange 8,

55 while the inner edge of said table is curved and provided with padding 9. The sides 4

are provided on their inner faces with padding 10 and the inner face of the back is provided with padding 11. The bottom or floor 5 may also be padded if desired. The 60 upper edges of the back 3 and the portions 6 of the sides 4 may be bound with soft material 12. A box 14 is provided in the rear portion of the chair and affords a space 14^a to which ready access may be had 65 through a door 15 in the lower portion of the back. The box 14 is provided with a double seat, one member 15 of which is made with a central opening and the other member 16 of which may be padded and hinged 70 to or otherwise movably connected with the member 15 or with the back 3 of the chair. Straps 17 (provided with suitable adjusting buckles) may be attached within the chair to hold the child in the rear portion of the 75 chair. Cross bars 18—19 are secured under the bottom 5 of the chair and disposed at right angles to each other, the cross bar 18 projecting appreciable distances beyond the front and back of the chair and the cross 80 bar 19 projecting appreciable distances laterally beyond the sides thereof. These cross bars thus form arms which project well beyond the vertical planes of the walls of the chair and are provided at their ends with 85 casters 20, and thus a broad supporting base is provided for the chair so as to prevent possibility of upsetting and yet permit the chair to be readily moved from place to 90 place.

Various slight changes might be made in the details of construction of my invention without departing from the spirit thereof or limiting its scope and hence I do not wish to restrict myself to the precise details herein set forth.

Having fully described my invention what I claim as new and desire to secure by Letters-Patent, is:—

1. A nursery chair comprising a floor and closed side, front and back walls sufficient in height to provide an inclosure for a child, a table mounted upon the top of the front wall and the forward portions of the side walls, a box seat within said inclosure, a 100 door in the back wall permitting access to the space within said box seat, said box seat having a top member provided with an opening, and a movable top member to normally cover the first-mentioned top member 105 of the box seat.

2. A nursery chair comprising a rectangu-

lar body having closed front, back and side walls and a floor, forming an inclosure for a child, arms secured to said floor and projecting forwardly, backwardly and laterally 5 from the edges of the floor, and casters at the free ends of said arms.

3. A nursery chair having solid back, front and side walls and a closed bottom, the back wall and portions of the side walls 10 projecting above the plane of the end of the solid front wall, padding on said side and back walls, a tray fixed to the upper end of the front wall and portions of the side walls, said tray having a curved and padded 15 inner edge, a commode compartment on the

closed bottom and opening through the back wall of the chair, a door closing said compartment, a movable cover for said commode compartment, arms secured to the bottom of the chair and projecting outwardly beyond the vertical plane of the several walls thereof, and casters near the outer ends of the several arms. 20

In testimony whereof, I have signed this specification in the presence of two subscribers. 25
